BRIDLE BIT

Anthony I. Gliha, Cleveland, and Oliver R. Ruple,
North Randle, Ohio

Application June 14, 1949, Serial No. 98,894

7 Claims. (Cl. 54—7)

1

This invention relates to bridle-bits and more especially to a bit for racing horses, and has for its main object to provide a bit having means under the control of the jockey for the prevention of bolting.

Another object of the invention is to provide a bit of said character which will not inflict punishment upon the horse but be effective in a nudging action for proper guidance and control of the horse in the running of a race.

Another object of the invention is to provide a bit of said character having a plain mouth-piece of cylindrical form between a pair of cheek-plates, one of which supports a plurality of slideable nudging pins operative at the will of the jockey.

A further object of the invention is to provide a bit of said character of simple construction, light weight, and consisting mainly of plastic material.

With the above and other objects in view, the invention will be hereinafter fully described with reference to the accompanying drawings, and the novel features thereof will be particularly pointed out in the appended claims.

In the drawings,

Figure 1 is a plan view of a bridle-bit constructed in accordance with our invention,

Fig. 2 is an end view thereof,

Fig. 3 is a section view of the left-hand portion of the bit taken on line 3—3 of Fig. 4,

Fig. 4 is an end view of Fig. 3,

Fig. 5 is a similar view to Fig. 3 of the right-hand portion of the bit,

Fig. 6 is an inner face view of a disc for supporting the nudging pins, and

Fig. 7 is a rear side view of the left-hand portion of the bit after the disc and the nudging pins supported thereby have been moved into nudging action.

Referring to the drawings, 1 represents a mouth-piece of cylindrical form and suitable length and made preferably of plastic material. The ends of the mouth-piece are reduced at 2 and 3 to provide shoulders at 4 and 5, and fixed securely to said reduced ends and abutting said shoulders are cheek-plates 6 and 7 of circular form, which are also made of plastic material. The cheek-plates 6 and 7 are provided with suitable and similar elongated strap openings designated by 8, 9 and 10 for attachment of the usual bridle straps and the reins. As shown, the strap opening 8, which is positioned directly above the mouth-piece 1, is provided for attachment of the head strap, and the lower opening 55

2

9, which is arranged on an angle, for attachment of the chin strap, and the larger rear opening 10, which is positioned directly back of the mouth-piece, for attachment of the reins.

5 The cheek-plate 6 is provided with a plurality of circular openings 11 which are in alignment with the longitudinal center of the mouth-piece 1 and arranged in a circle concentric therewith, and the inner end edges of said openings are 10 cupped out at 12. Slidably mounted in each of the openings 11 of the cheek-plate 6 and extending outwardly therefrom is a nudging pin 13 having an enlarged ball-shaped head 14, the inner portion of which, indicated by 15, is adapted to enter the cupped out edge portion 12 of the opening 11. For supporting the nudging pins 13, a disc 16 of plastic material and less in diameter than the cheek-plate 6, is provided with bores 17 of smaller diameter than the nudging 15 pins and arranged in a circle corresponding to that of the openings 11. The outer ends of the nudging pins 13 are reduced at 18 to fit into the bores 17 and leave shoulders at 19 for engaging the disc 16. Said reduced ends 18 of the nudging pins 13 are cemented in the bores 17 of the disc 16. In normal position, the nudging pin disc 16 is forced outwardly from the cheek-plate 6 by means of a coiled spring 20, the inner end of which fits over the reduced end 2 of the mouth-piece 1 and engages said cheek-plate and its outer end rests in a circular groove 21 of the nudging pin disc. The heads 14 of the pins 13 limit the outward movement of the disc 16 relative to the cheek-plate 6.

30 35 For enabling the jockey to actuate the disc 16 inwardly against the outward action of the spring 20 and thereby cause the outer ends of the heads 14 of the nudging pins 13 carried by said disc to contact the cheek of the horse, the following means is provided:

The mouth-piece 1 is hollowed by boring through its entire length as indicated at 22, and fixed in a central opening 23 of the disc 16 by means of nuts 24 and 25 at each side thereof is a threaded pin 26 extending inwardly and located opposite said bore. Fixed to the free inner end of the pin 26 is a length of flexible wire 27, which passes through the bore 22 of the mouth-piece 1 and terminates at its outer free end in a loop 28 for attachment of a suitable pull-strap 29 for the use of the jockey. The wire 27 is securely fixed to the threaded pin 26 by providing the end of the pin with a bore 30 for receiving said wire and crimping it therein as indicated at 31. For reducing both the friction and the wear upon

the flexible wire 27 due to moving contact with the inside of the mouth-piece and the flexing of the wire at the turn, the outer periphery of the end of the bore 22 of the mouth-piece is curved and flared outwardly as at 32.

In practice, the usual head strap of the bridle is connected to the openings 8 of the cheek-plates 6 and 7, the usual chin strap is connected to the openings 9 of said cheek-plates, and the reins are connected to the openings 10 of said cheek-plates. The cylindrical piece 1 is placed in the mouth of the horse, the cheek-plates 6 and 7 at each side thereof, and the bridle straps are properly adjusted and fastened. The disc 16 carrying the nudging pins 13 is normally forced to the left and away from the cheek-plate 6 by the action of the spring 20 and the heads of the nudging pins 13 are out of contact with the sides of the horse's lips. If when running a race, the horse has a tendency to turn its head to the left, the jockey pulls upon the strap 29, and through same, the flexible wire 27 and the pin 28, thereby forcing the disc 16 to the right against the action of the spring 20 and causing the heads 14 of the nudging pins 13 to contact the left side of the horse's lips and cause the horse to turn its head in the opposite direction. By alternate pulling and releasing of the strap 29, the jockey is able to control the tendency of the horse to bolt and thereby cause it to keep its head in a straight-forward position and thus avoid lost motion and time in the running of the race.

The bit shown and described is for a horse with a tendency to bolt to the left and the nudging pins are at the left for action to the right, but for a horse having a tendency to bolt to the right, the bit would be reversed thereby placing the nudging pins at the right for action to the left against the right side of the horse's lips, and the jockey would hold the pull-strap in his left hand.

From the foregoing, it is apparent that bit is light in weight, easy on the mouth of the horse, and that by its use, a race horse with a tendency to bolt would be under the control of the jockey due to the nudging action exerted through his use of the pull-strap, and that by thus maintaining the horse's head in a straight-away position on the track, loss in running time from bolting would be eliminated.

Having fully described our invention, what we claim is:

1. In a bridle-bit, the combination of a mouth-piece, a cheek-plate fixed to each end of the mouth-piece, pins supported in one of the cheek-plates and adapted to move longitudinally relative to the mouth-piece, a disc supporting said pins, a spring tending to force the disc in one direction, and means for manual movement of said disc in the other direction.

2. In a bridle-bit, the combination of a mouth-piece, a cheek-plate fixed to each end of the mouth-piece, pins slidably supported in one of the cheek-plates, the pins having heads at their inner ends, a disc, the outer ends of said pins fixed to said disc, a spring between said disc and cheek-plate supporting said pins tending to force said disc and said pins in one direction, and means for causing manual movement of said disc and said pins in the other direction to move the heads of said pins into contact with the lips of a horse in a nudging action.

3. In a bridle-bit, the combination of a mouth-piece, a cheek-plate fixed to each end of the

mouth-piece, pins slidably supported in one of the cheek-plates, a disc supporting the pins, the pins having heads at their inner ends, a spring between said disc and the cheek-plate supporting said pins and tending to force the heads of the pins against the cheek-plate, the mouth-piece being hollow, and means passing through said mouth-piece and fixed to said disc for manually moving said disc against the action of said spring for causing the heads of said pins to nudge the side of the lips of the horse.

4. In a bridle-bit, the combination of a mouth-piece, a cheek-plate fixed to each end of the mouth-piece, members movably supported by one of the cheek-plates, a disc supporting the members, a spring normally forcing the disc outwardly, the mouth-piece being hollow, and a wire passing through said mouth-piece and fixed to said disc for manually moving same inwardly for causing said members supported thereby to contact the side of the lips of a horse.

5. In a bridle-bit, the combination of a mouth-piece, a cheek-plate fixed to each end of the mouth-piece, members slidably supported by one of the cheek-plates, a disc, the members having their outer ends fixed to the disc, a spring adapted to force the disc outwardly, the mouth-piece having a bore throughout its length, a pin fixed to said disc and opposite the bore of the mouth-piece, and a length of flexible material secured to said pin and extending through the bore of the mouth-piece for manually forcing said disc and the members supported thereby inwardly to cause said members to contact the sides of the lips of a horse.

6. In a bridle-bit, the combination of a mouth-piece, a cheek-plate fixed to each end of the mouth-piece, pins slidably supported in one of the cheek-plates, the pins having heads at their inner ends, a disc, the outer ends of the pins being fixed to the disc, the mouth-piece having a bore for its entire length, a bolt fixed to said disc and opposite the bore of the mouth-piece, the disc having a circular groove in its inner face and around said bolt, a coiled spring seated in said groove and engaging said cheek-plate supporting said pins and tending to force said disc outwardly, and a length of flexible wire fixed to said bolt and extending through said bore of the mouth-piece beyond its end, the free end of the flexible wire terminating in a loop for attachment of a strap for pulling action of the jockey.

7. In a bridle-bit, the combination of a mouth-piece, a cheek-plate fixed to each end of the mouth-piece, members movably supported by one of the cheek-plates, a disc supporting the members, means tending to force the disc and members outwardly, and manual means for forcing said disc and members inwardly, the cheek-plates being provided with openings for attachment of the head strap, the chin strap and the reins.
